(57) **CLAIM**

We claim the ornamental design for a blade, as shown and described.

DESCRIPTION

FIG. 1 is a front perspective view of a blade showing our new design;

FIG. 2 is a front elevation view thereof;

FIG. 3 is a top plan view thereof;

FIG. 4 is a bottom plan view thereof; and,

FIG. 5 is a side elevation view thereof which is also a mirror image of the opposite side thereof.
